US0D1011302S

(12) **United States Design Patent** (10) **Patent No.:** **US D1,011,302 S**
(45) **Date of Patent:** **** Jan. 16, 2024**

(54) **TELEVISION RECEIVER**

(71) Applicant: **LG ELECTRONICS INC.**, Seoul (KR)

(72) Inventors: **Woosuk Park**, Seoul (KR); **Misun Park**, Seoul (KR)

(73) Assignee: **LG ELECTRONICS INC.**, Seoul (KR)

(**) Term: **15 Years**

(21) Appl. No.: **29/741,759**

(22) Filed: **Jul. 15, 2020**

(30) **Foreign Application Priority Data**

Jan. 17, 2020 (KR) 30-2020-0002420

(57) **CLAIM**

The ornamental design for a television receiver, as shown and described.

DESCRIPTION

FIG. 1 is a front perspective view of a television receiver showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof; and,

FIG. 8 is a front perspective view of the television receiver of FIG. 1 shown in an alternate configuration of use.

1 Claim, 8 Drawing Sheets
